UNITED STATES PATENT OFFICE.

ALFRED W. CHAPMAN, OF CLEVELAND, OHIO, ASSIGNOR TO THE DONLEY BROTHERS COMPANY, OF CLEVELAND, OHIO, A CORPORATION.

FIREPLACE-DAMPER ADJUSTER.

Application filed May 12, 1927. Serial No. 190,805.

This invention relates to means for holding in position and adjusting the degree of opening of dampers in the chimney flues of fireplaces; and it refers more particularly to 5 such means designed to be shifted by a fire poker.

Poker-operated fireplace damper controllers of the class shown in the patent to Harry N. Cain, No. 1,415,522, May 9, 1922, 10 are suitable for fireplaces having dampers and flue throats level with or but slightly above the main arch or lintel of the fireplace front; but when such dampers and throats are set some inches or a foot above the fireplace opening, as has now become more approved practice in fireplace design, it results in locating the damper controller so high up in the chimney that it cannot be seen from in front of the fireplace, and is, therefore, very 15 difficult or impossible to reach and operate with a poker, or any implement.

Wherefore, the prime object of my present invention is to provide convenient and accessible means for adjusting a fireplace damper, even though the damper is set some 25 distance above the arch or lintel of the fireplace. Another important object is to provide a controlling device adapted to open a fireplace damper by a pull with a hook-ended poker engaged therewith, instead of a 30 push as heretofore required, it being much more natural and convenient for an operator to pull a poker forward and away from the fire than to push it backward; and the 35 poker will not slip out of or through the operating ring when pulled, as it is apt to do when pushed. Further objects are to produce a damper regulating device adaptable to the height of the damper above the 40 fireplace opening; which is arranged to operate freely and prevent clogging; and which is simple, efficient and inexpensive to install.

Minor advantages will become apparent 45 from the following description of a preferred form of my invention, reference being had to the accompanying drawing, in which—

Fig. 1 is a sectional elevation from front to rear of a part of a chimney and fireplace 50 showing a damper with my improved adjusting means set therein.

Fig. 2 is a top view,

Fig. 3 is a side view, and

Fig. 4 is a front view of the adjusting

device enlarged and disconnected from the 55 damper.

The reference numeral 1 indicates the upper part of a fireplace opening and 2 the lower end of a smoke flue, as ordinarily arranged in a house chimney 3. As usually 60 constructed an iron damper frame is set in the masonry of the chimney, and comprises a hollow, wedge-shaped body 4, its open bottom conforming to the top of the fireplace, its sides and ends inclined inwardly, and a 65 surrounding horizontal flange 5 forming its base. The rear part of the flange 5 rests upon the shelf 6 at the bottom of the flue 2, and its forwardly projecting portion, together with the inclined front of the body 70 4, spans the fireplace 1 and assists in supporting the wall above it. The inclined rear side of the body 4 rises but slightly above the flange 5, thus forming a large rectangular flue orifice 7 in the rear slope of the 75 damper frame.

A flat-faced damper door 8 adapted to open and close the orifice 7 is mounted to turn in suitable sockets 9, as shown upon the rear slope of the frame body 4, or the 80 damper may be hinged in any approved way at its lower edge to the frame. Thus the damper closes by gravity, unless it is opened to the extreme position shown by dotted lines in Fig. 1.

The adjuster comprises a straight rack-bar 85 10 of rectangular section hinged at its lower end by a removable cotter pin 11 between a pair of depending ears 12 of the damper frame 4, and said bar has ratch-teeth 13 90 formed in its upper edge. Diagonally opposed standards with their tops connected together as at 14, are extended up from the sides of the bar 10 at its upper end, and form a self-cleaning, rectangular guideway loop 95 through which a pawl-bar 15 may loosely slide.

The pawl-bar 15, which is also straight and of substantially rectangular section, is hinged at its upper end, preferably by a 100 cotter pin 16, between a pair of ears 17 projecting from the under face of the damper door 8; both the bars 10 and 15 being hinged to swing vertically. The lower end of the bar 15 is bent downward and beveled to a thin edge, as at 18, so as to form a detent fitted to engage the ratch-teeth 13 when sliding downward.

The rack-bar 10 has a short arm 19 depending from its lower end, to which are hinged, one on each side of it, by a bolt 20 a pair of flat and substantially parallel bars 21 and 21^a to make a link connection. The operating lever is preferably formed of a pair of flat, parallel bars 22 and 22^a depending from a hinge-bolt 23 passed through the pawl-bar 15 adjacent to its detent 18, and loosely embracing the rack-bar 10 to guide the slideable pawl-bar, and keep the detent 18 properly aligned with the ratch-teeth 13. The links 21 and 21^a overlap the lever bars 22 and 22^a respectively, and are hinged to the latter by a bolt 24, so that the links normally lie nearly at right angles to and provide an oscillatory, self-adjusting fulcrum for the operating lever. A ring-shaped handle 25 depends from the lower end of the operating lever, being preferably formed beneath a flat shank 26 which is inserted and riveted, as at 27, between the flat bars 22 and 22^a.

To adjust the damper to regulate the draft of a fire, an ordinary hook-ended poker may be used to engage the handle ring 25, as indicated by dotted lines in Fig. 1; a forward pull on the handle ring rocking the upper end of the operating lever and the pawl-bar 15 backward, thereby opening the damper door 8 while the detent 18 contacts by gravity with and slips back over the ratch-teeth 13; the detent engaging one of said teeth to hold the damper in corresponding position when the operator stops pulling on the ring. An upward push on the ring 25 releases the ratch pawl 18 from the teeth 13, and permits the damper to close by gravity. If the damper door is swung back over its center the lever bar 22 stops against the guide 14, and a push on the ring 25 readily throws it over to gravity-closing position. The guideway at the rear end of the rack-bar 10 is beveled at its bottom and top, as shown at 28 and 29 in Figs. 3 and 4, so that the pawl-bar and operating lever can be raised until the bolt 24 stops against the rack-bar to dislodge any accumulations of soot which may form on the device.

Until recently it has been common practice to set the damper frame level with the top of the fireplace opening, the latter being at 30, Fig. 1, and the front part of the flange 5 serving as a lintel supporting the fireplace arch; but in later approved designs the damper and chimney shelf 6 are

set a distance depending on size and preference above the opening, so that the lintel or arch is relatively lowered to a position 31, as shown. Thus the necessity for providing a handle-ring 25 positioned lower down than those found in existing damper controls should be readily understood. It is also obvious that the length of the operating lever 22 can be varied to correspond with varying heights of the damper above the arch 31, so that the ring 25 can easily be seen and engaged with a poker, and yet remain ordinarily hidden from the view of the occupants of the room.

I further point out and distinctly claim as my invention:

1. An adjuster for dampers comprising a pair of interlocking bars adapted to connect a damper with a fixed support, one of said bars being slideable longitudinally upon the other bar, and an operating lever hinged to and pendant from said slideable bar having an oscillatory fulcrum pivoted upon the other bar.

2. An adjuster for dampers comprising a pair of interlocking bars adapted to connect a damper with a fixed support, one of said bars being slideable longitudinally upon the other bar, an operating lever hinged to and pendant from said slideable bar, and a link connection between the operating lever and a depending arm of said other bar.

3. An adjusting device for dampers comprising a rack-bar having a guideway loop at its free end, a pawl-bar slideable in said loop upon the rack-bar and engageable with ratch-teeth on the latter to prevent shortening the device, an operating lever pendant from its hinge connection to the pawl-bar and embracing the rack-bar, and means forming an oscillatory fulcrum for the operating lever on the rack-bar.

4. An adjusting device for dampers comprising a rack-bar having a guideway loop at its free end and a pendant arm on its attachable end, a pawl-bar slideable in said loop upon the rack-bar and engageable with ratch-teeth on the latter to prevent shortening the device, an operating lever pendant from its hinge connection to the pawl-bar and embracing the rack-bar, a link connection between the operating lever and said arm of the rack-bar, and a terminal handle-ring on the operating lever.

ALFRED W. CHAPMAN.
